CONTINUOUS MOTION WRAPPING MACHINE

Elmer L. Smith, Longmeadow, and Carlton Wetsel, Springfield, Mass., assignors to Package Machinery Company, Springfield, Mass., a corporation of Massachusetts

Application July 28, 1936, Serial No. 92,972

7 Claims. (Cl. 93—2)

This invention relates to machines for wrapping articles, and has particular reference in some of its aspects to such machines when designed to operate continuously with respect to the manner in which the article is forwarded through the machine.

In some particulars the machine is an improvement over those of the type employing two continuously moving article forwarding conveyors arranged at right angles to each other. The first conveyor of machines of this type carries the article through wrapping mechanism which folds the wrapper around five sides of the article, leaving a tubular wrapper extension at the rear. In order to disengage the article from the first conveyor in order to permit it being carried by the second conveyor in a direction at right angles to that of its original travel the article pushers of the first conveyor have previously been arranged to withdraw rearwardly from the tubular extension as they approached the position where the article was to change its direction of travel. This construction proved to be the limiting factor as to the permissible speed of travel of the conveyors on account of the inertial factors set up by the reversal of movement of the pushers and the frictional forces due to the cam mechanism which was required. It is one object to improve machines of this type so that the construction of the first conveyor can be simplified and the speed of the machine materially increased. In accordance with the present invention this is done by moving the article ahead of the first pushers instead of moving these pushers rearwardly with respect to the article. In the preferred embodiment this additive forward movement of the article is accomplished by mechanism which operates to position the article against an abutment with no tendency to rebound even when the machine is operated at very high speeds. In actual production the machine of the present invention has been operated at speeds up to 280 articles per minute, the articles being of a size which have been wrapped on previous machines at a maximum speed of 125 articles per minute.

A further object is to improve the means for supplying a sealing liquid to the wrappers, whereby there will be no danger of an oversupply of sealing liquid when the machine is temporarily stopped.

A further object is to improve the means for delivering the articles at high speed from the machine so that they can be handled effectively at very high speed.

Additional objects will appear from the following description and claims.

Referring to the drawings,

Fig. 1 is a plan view of the machine, with certain parts broken away;

Fig. 2 is a detailed vertical section, on an enlarged scale, of the terminal portion of the first conveyor and the mechanism for moving the article forwardly out of range of this conveyor into position for being picked up by the second conveyor, the parts being shown in a position where the article is still being carried by the pushers on the first conveyor;

Fig. 3 is a detail perspective of certain of the parts shown in Fig. 2, illustrating the manner in which the article is engaged and carried ahead of the first pushers;

Fig. 4 is a side elevation of the machine, showing the paper feed and the first conveyor, certain parts being broken away for clarity;

Fig. 5 is a view similar to Fig. 2 but showing the parts in the positions they occupy at a later time;

Fig. 6 is an enlarged vertical section showing the manner in which the article is engaged by the pushers of the first conveyor;

Fig. 7 is a section on line 7—7 of Fig. 6;

Fig. 8 is a longitudinal section through the second conveyor, taken on line 8—8 of Fig. 1;

Fig. 9 is a detail of the terminal portion of the second conveyor and of the article stacking mechanism, looking from the opposite side of the second conveyor from Fig. 8;

Fig. 10 is a detail similar to Figs. 2 and 5 showing a still later stage in the forwarding of the article;

Fig. 11 is a perspective detail of the article as it is being carried along by the second conveyor, showing the making of the front and rear tucks in the tubular wrapper extension;

Fig. 12 is a detail of the driving connections for the rotary folder and sealing liquid applying device shown in Fig. 8;

Fig. 13 is a section on line 13—13 of Fig. 1, showing the article feeding-in conveyor;

Fig. 14 is a section on line 14—14 of Fig. 1, showing the first conveyor and its associated folding and sealing mechanism;

Fig. 15 is a section on line 15—15 of Fig. 1, showing the first conveyor and the associated sealing mechanism; and

Fig. 16 is a detail side elevation, looking from the opposite side of the machine from that shown in Fig. 4, showing the driving means for the wrapper feed.

The description of the machine will be begun with the wrapping machine proper, leaving the wrapper feed and the article feeding-in conveyor for later consideration. The frame 20 of the machine carries a bed plate or table 21 upon which the articles are supported during their travel. Underneath this bed are supported a pair of spaced horizontal shafts 22 and 23, carrying pairs of sprockets 24 and 25 respectively. Spaced chains 26 are carried by these sprockets, and serve to carry the first series of pushers in a manner to be described. The chains travel continuously, and their upper runs are supported by rails 27 (Fig. 15) supported from the frame by brackets 28. The shaft 23 bears a pulley 29 (Fig. 4), coupled to a pulley 30 on the shaft 31 of a suitable motor by a belt 32. This belt is made long enough so that it will be slack except when tensioned by a pulley 33 mounted on arms 34 pivoted to the frame at 35. The pulley is shown in Fig. 4 in belt-slackening position in full lines, and in belt-tightening position in dotted lines. For operating the tightening pulley one of the arms 34 is connected by a link 36 with an arm 37 on a shaft 38 mounted in the frame and provided with a handle 39. By swinging this handle the first conveyor, as well as all the other moving mechanism, can be started or stopped at the will of the operator. The same handle controls the operation of the first sealing liquid applying mechanism in a manner to be described.

The parallel chains 26 are bridged at intervals by pairs of bars 40 (Figs 2, 7 and 15) suitably secured to the chain links. Welded to the forward one of each pair is a plate 41 bearing at its upper end a pusher 42. The plate 41 is not secured to the rear bar of the pair, as is best shown in Fig. 10, this bar acting as a support only when the chain is passing along the straight part of its run as shown in Fig. 2. The pusher passes to its positions above and below the bed 21 through holes 43 and 44 (Fig. 1), while the plate extends during the straight part of its run through a slot 45 (Fig. 3). The forward end of the pusher contacts the rear end of the article to be moved, and preferably is provided with a small downwardly extending lug 46 which as shown in Fig. 6 lies within the slot 45 to insure that adequate contact will be made with the lower edge of the article. The article is more rigid at this point than at the central portion of its end, and the described construction insures that the pusher will cause no damage to the article end. The wrapper is folded around the article and also around the lug 46, as will be described further on and as is shown in Fig. 2, but the lug is of insufficient size to cause any deleterious distortion of the wrapper at this point.

The article, which is fed into position in front of one of the pushers in a manner to be described, is carried forward by this continuously traveling pusher so as to contact a wrapper *w* fed downwardly through a slot 50 (Fig. 14) in the bed 21. The wrapper is folded over the top and bottom of the article by contact with a top plate 51 and with the bed 21 respectively. Side tucks *b* (Fig. 3) are formed by tucking plates 52 (Fig. 14) and side folds *c* and *d* by plates 53 and 54. These stationary folders are of the standard type and detailed description is unnecessary. After the tucks *b* and the upper side folds *c* are made the lower extending side flaps *d* pass underneath wheels 55, the operation of which will be considered in more detail below, and receive a stripe of sealing liquid on their upper

surfaces which serves to cause them to adhere to the folds *c* when the flaps *d* are folded into contact with them by the final folding plates 54. The package then passes between heating plates 56 (Fig. 1), preferably spring pressed together in the usual manner as by flat springs 57, which cause thorough adherence of the flaps and evaporate any excess of sealing liquid. The packages are then carried by the continuously moving pushers between holding plates 58 which are preferably set so as to hold the sides of the package with somewhat less force than was exerted upon them by the heaters. It is between these latter plates that the article is engaged by the secondary forwarding means which frees it from the pushers.

This secondary feeding means comprises a lug 60 (Fig. 2) carried by a chain 61 supported on sprockets 62 and 63. The chain is mounted centrally of the first wrapping channel, as is shown in Fig. 1, and is driven at a surface speed somewhat greater than the speed of the pushers 42. Fig. 2 shows the article being forwarded by the pushers 42 and the lug 60 about to round the sprocket 62 into position to engage the rear side of the article. It will be remembered that the wrapper at this time has been folded completely around the article except for its rear side; and in order to contact the rear end of the article it is necessary to bend the tubular extension of the wrapper downwardly so that the lug 60 can bear against the upper rear corner of the article, without forming a fold which will interfere with the later folding operations to be performed in the second folding channel. In order to permit this false fold to be made without any permanent creasing of the wrapper the lug 60 is, in accordance with the present invention, made with a convex article-contacting face 64 which is preferably in substantially the form of a quadrant of a circle. The manner in which the curved face 64 initially contacts the article and produces this false tuck is shown in Fig. 3. At the time when this contact is made the article has passed the heaters 56 and is located between the plates 58 which, as stated above, are preferably less firmly pressed against the article than the heaters. The article is thus comparatively free, and can be given a rapid forward acceleration by the lug 60 without the latter exerting a pressure on the wrapper great enough to permanently crease it.

In Fig. 5 the article is shown as being cleared entirely from the pusher 42 which initially engaged it, and as being on its way towards the abutment 65 which stops its forward motion in position to be engaged by the second conveyor. At the time of engagement of the leading end of the article with this abutment the lug 60 is elevated by reason of the chain which carries it passing around the sprocket 63. During this motion the curved form of the contacting face of the lug again comes into play, the curved surface of the lug sliding smoothly over the upper rear edge of the article and exerting no force tending to strip the wrapper therefrom. The slippage of the lug over the article edge also has the function of permitting the article to come to rest with a gradual motion and preventing any rebound when the article strikes the abutment. This is of considerable importance, as the speed of the article along the channel is very high, and even a slight rebounding action would shift the final position of the article sufficiently to cause

it to jam when the second conveyor started to carry it along the second folding channel.

The second folding channel is formed by the plate 21 acting as a floor, and by side guides 66 and 67. The former of these is conveniently formed as a continuation of the abutment 65, and the leading end 68 (Fig. 8) of the latter acts as a tucker for what is now the leading side of the tubular extension of the wrapper. A removable top plate 69, omitted from Fig. 1 in order to reveal other parts, holds the articles in position above the bed. The articles are carried in succession along the second folding channel by T-shaped pushers 70 mounted on a centrally disposed chain 71 passing over a terminal sprocket 72, a driven sprocket 73, and an idling and tightening sprocket 74. The pushers 70, like the pushers 42, move continuously, but since there is no longer any rearwardly projecting wrapper extension there is no longer any necessity of having these pushers constructed with a forwardly projecting portion. They are therefore made in simple block form, their stems passing through a slot 75 (Fig. 11) in the bed 21. At the end of the second channel adjacent the first channel the T-shaped pushers 70 swing upwardly beyond the end of the bed, while at the other end they swing downwardly through an aperture 76 (Fig. 1).

While the package is against the abutment 65 the rear tuck *d* in the tubular extension is turned in by a blade 80 (Figs. 8 and 11) on a rotary folding wheel 81. This wheel is driven continuously in a manner to be described, and has a plurality of blades arranged to contact successive articles. The blade turns in the rear tuck at about the time the article is engaged by the pusher 70. The speed of the pusher is preferably higher than the speed of the blade, so that the article is carried away from the latter. However, even if the blade in its circular movement strikes against the lower extending flap the contact will be for such a short time and over such a slight area, that the bending of the flap will give it no bend which will not be taken out by the later action of the folding plate. The front tuck *e* is, as before described, made by the tucker 68. After the formation of the tucks the lower flap *f* is carried over a wheel 82 dipping into a trough 83 and serving to apply a stripe of sealing liquid to the lower side of the flap. The flap *f* is folded upwardly by a stationary folding plate 84, and the upper flap *g* is folded downwardly over it by a stationary folding plate 85. The completely wrapped package then passes between heaters 86 and cooling plates 87.

The packages have proceeded thus far along the second folding channel in a spaced relation determined by the spacing of the pushers 70. They are now assembled in overlapping relationship so as to facilitate their removal from the machine. Due to the extremely high speed at which the machine is designed to operate it would be difficult to dispose of the wrapped packages with sufficient rapidity were they to be fed into the delivery chute in the customary end to end relation. In accordance with the present invention the articles are both tilted and overlapped so that they can be picked up manually in groups without handling the articles individually.

As the pushers 70 descend through the aperture 76 the articles are left upon the bed 21 and are carried forward from that point solely by the pressure of the articles following them. The wrapped articles are thus forced in a con-

tinuous stream up a slanting riser or ledge 88, and are kicked downwardly into the overlapping relationship shown in Figs. 8 and 9 by an oscillating paddle 89 which makes one downward stroke for each article. The high speed of the machine is here utilized for obtaining the desired relationship, since the articles are projected beyond the end of the riser with such speed that they do not have a chance to turn or fall until they are struck by the paddle and carried downwardly at the desired angle. They come to rest on a delivery conveyor 90 provided with spacing lugs 91 which support the articles the desired distance apart and with the proper slant so that they continue in their overlapping position. This delivery conveyor is driven as by a chain and sprocket connection 92 from the shaft 93 of the terminal sprocket 72 of the second conveyor, and is hence driven in timed relation to that conveyor but at a lower speed.

The paddle 89 is secured to a shaft 94 (Figs. 1 and 9) journaled in suitable bearings and having fixed to it an arm 95 at the lower end of which is a collar 96 through which a rod 97 slides freely. The other end of this rod is pivoted to a crank pin 98 on a crank 99 carried by the shaft 93. A spring 100 bears against the collar 96 at one end and at the other against a collar 101 fixed on the rod 97. A second collar 102 also fixed to the rod bears against the side of the collar 96 opposite the spring. By this means the paddle is oscillated upwardly with a positive motion and downwardly with a yielding connection so that if the packages become jammed the paddle will not crush them.

The articles are fed into the machine by a belt conveyor 105 which carries them in a continuous stream between side guides 106 against a stop 107. The belt 105 is driven by a pulley 108 rotated through bevel gearing 109 from the shaft 22. The speed of the belt is set so that the forward motion of the articles is practically continuous, the articles being picked up one at a time from their position against the stop 107 by the pushers 42.

The wrapping material is supplied to the machine from a reel 110, and is regulated in its tension by the usual brake 111 and tension roller 112. The web is forwarded by a pair of feed rolls 113 and 114 which rotate continuously and are journaled in a plate 115 adjustable vertically on posts 116 by a hand screw 117. The roll 113 is provided with a gear 118 (Fig. 16) meshing through a change gear 119 with a gear 120 on a cutter shaft 121 also journaled in the plate 115. This cutter shaft is coupled through a chain and sprocket connection 122 with a shaft 123 journaled in a J-shaped bracket 124 pivoted on the shaft 22 and having an arcuate bolt and slot connection 125 with the frame. By swinging the bracket 124 around the shaft 22 the chain 122 can be kept tight in any position of vertical adjustment of the paper feed mechanism. The cutter shaft 121 carries a rotary cutter blade 126 coating with a stationary blade 127. The feed roll 114 is preferably mounted on a bracket 128 pivoted on the plate 115 and carrying at its upper end a pivoted yoke 129 adapted to fit over a spring pressed stud 130 and against a suitable stop 131. The web is fed downwardly at a constant rate by the feed rolls into a guide way formed by the upturned end 132 of the top plate 51 (Fig. 14) and a guide plate 133. The cutter is timed to sever a sheet just as the lower end of the web is engaged by the article.

so that the web itself is never brought to rest and no terminal stop on the paper guideway is necessary. If a material like some of the regenerated cellulose wrappers is to be used it may be preferable to provide stationary interfitting wire guides 134 to impart a temporary longitudinal crimp to the web and thus increase its rigidity in a known way.

The first adhesive applying rolls 55 are mounted upon squared shafts 135 (Figs. 1 and 15) journaled in brackets 136 and 137. The brackets 136 have a screw and slot connection 138 with the brackets 137, so that the rolls can be shifted laterally to accommodate different article widths, and the latter bracket has a rib 139 (Fig. 15) which serves to keep the bearing bracket 136 always in proper alignment. Each squared shaft 135 is joined by a chain and sprocket connection 140 with a shaft 141 also journaled in the brackets 137 at a point underneath the bed 21. The latter shaft is provided with sprockets 142 which engage the lower runs of the chains 26 and perform the double function of supporting these chains at an intermediate point of their length and of drawing power from them to operate the rolls 55.

The sealing liquid is supplied to the rolls 55 from reservoirs 145 (Figs. 1 and 4) of the fountain feed bottle type held between a stand 146, provided with a suitable well, and an upper clamp 147. Both the stand and the clamp are mounted on a vertically movable rod 148 for a purpose to appear. A flexible tube 149 joins each of the stands 146 to an open topped funnel-shaped feeder 150 associated with one of the rolls 55. The feeder 150 is formed with a side slot within which the roll fits snugly. As long as the roll is rotating in a direction to pass downwardly through the slot it will carry a quantity of liquid determined by the clearance between the roll and the slot walls. When the machine is stopped, however, the liquid would tend to ooze out the space between the wheel and the feeder slot, and mechanism has therefore been provided for preventing this by lowering the fountain feed coincidentally with the stopping of the machine and to a sufficient degree to cause the liquid to drain backwardly out of the feeders.

For this purpose the shaft 38 which carries the machine controlling handle 39 is provided, as best shown in Fig. 4, with arms 151 positioned to contact the lower end of each of the rods 148 when the handle is in its belt-tightening position. As long as the machine is running the fountain feed is therefore raised into an operative position, but when the machine is stopped the fountain feed will be lowered so that it is no longer effective to maintain a level of liquid in the feeder 150. The elevation at which the fountain feed is maintained when the machine is at rest can be regulated by an adjustable stop 152.

The described arrangement of parts lends itself to a very simple driving mechanism. Power being supplied to the shaft 23 as described the first conveyor is driven directly from that shaft; and the feeding-in conveyor, the paper feed, and the first sealing liquid applying rolls, are all driven from the first conveyor. The short forwarding conveyor 61 is driven from the shaft 23 by a chain 155 passing around a sprocket on the shaft and around an idler sprocket 156 (Fig. 4), engaging on its outer surface with a sprocket 158 on the shaft 158 of the conveyor sprocket 63. The shaft 160 (Fig. 12) which carries the sprocket 73 of the second conveyor is driven from the shaft

23 by bevel gears 161 (Fig. 1). The shaft 160 also carries a sprocket 162 joined by a chain 163 with a sprocket 164 on the shaft of the rotary folder 81 and with a sprocket 165 on the shaft of the sealing liquid applying wheel 82.

5

We claim:

1. A wrapping machine comprising two wrapper folding channels at right angles to each other, a continuously moving series of article forwarding pushers passing through the first channel and each having a forwardly extending portion, the first channel and said pushers being so coordinated that as an article and wrapper are forwarded through said channel by each of said pushers the wrapper will be folded around five sides of the article and around the forwardly extending portion of said pusher, a second series of continuously moving article forwarding pushers carrying the articles through the second channel, and supplementary article forwarding means contacting the rear sides of articles being forwarded by the pushers of the first series and moving said articles ahead of said pushers into position to be received by the pushers of the second series. 15

2. A wrapping machine comprising two wrapper folding channels at right angles to each other, a continuously moving series of article forwarding pushers passing through the first channel and each having a forwardly extending portion of less area than the face of the article with which it contacts, the first channel and said pushers being so coordinated that as an article and wrapper are forwarded through said channel by each of said pushers the wrapper will be folded around five sides of the article and around the forwardly extending portion of said pusher, a second series of continuously moving article forwarding pushers carrying the articles through the second channel, an endless conveyor positioned parallel to and adjacent to the line of movement of the pushers of the first series and traveling at a higher rate of speed than said pushers, and one or more pushing elements carried by said conveyor in position to engage the rear of the article engaged by a pusher of the first series by pressure exerted through the tubular extension of the wrapper. 30

3. A wrapping machine comprising two wrapper folding channels at right angles to each other, a continuously moving series of article forwarding pushers passing through the first channel and each having a forwardly extending portion of less area than the face of the article with which it contacts, said forwardly projecting portion having a lug extending into position to overlap one edge of the rear of the article and to cause the article to be forwarded by pressure exerted on said edge, the first channel and said pushers being so coordinated that as an article and wrapper are forwarded through said channel by each of said pushers the wrapper will be folded around five sides of the article and around the forwardly extending portion of said pusher and said lug, a second series of continuously moving article forwarding pushers carrying the articles through the second channel, an endless conveyor positioned parallel to and adjacent to the line of movement of the pushers of the first series and traveling at a higher rate of speed than said pushers, and one or more pushing elements carried by said conveyor in position to engage the rear of an article engaged by a pusher of the first series by pressure exerted through the tubular extension of the wrapper and to move said article forwardly to clear the tubular wrapper exten- 75

sion from the forwardly projecting portion of said pusher and from said lug.

4. A wrapping machine comprising two wrapper folding channels at right angles to each other, a continuously moving series of article forwarding pushers passing through the first channel and each having a forwardly extending portion of less area than the face of the article with which it contacts, the first channel and said pushers being so coordinated that as an article and wrapper are forwarded through said channel by each of said pushers the wrapper will be folded around five sides of the article and around the forwardly extending portion of said pusher, a second series of continuously moving article forwarding pushers carrying the articles through the second channel, an endless conveyor positioned parallel to and adjacent to the line of movement of the pushers of the first series and traveling at a higher rate of speed than said pushers, and one or more pushing elements carried by said conveyor and having a pushing surface substantially in the form of a quadrant of a circle to engage the rear edge of the face of an article engaged by a pusher of the first series by pressure exerted through the tubular extension of the wrapper, and to pass out of contact with said edge gradually so as to leave the article in position to be engaged by a pusher of the second series without leaving a permanent fold in the tubular extension of the wrapper.

5. A wrapping machine comprising a channel, means for forming a wrapper into a tube enclosing five sides of an article and extending rearwardly as a tubular extension beyond the sixth side, and a conveying member constantly advancing in an endless path at one side of the channel, said path being so located that the member enters and leaves the channel in tilted position, the member being curved on its pushing face so as to leave the article with a sliding movement as the member tilts in its withdrawal from the channel and shaped to contact the par-

tially wrapped article on one rear corner by pressing against said corner a portion of the wrapper throughout an area insufficient to form a permanent fold therein.

6. A wrapping machine comprising a channel, means for forming a wrapper into a tube enclosing five sides of an article and extending rearwardly as a tubular extension beyond the sixth side, a fixed stop positioned to arrest movement of the article along the channel, and a conveying member constantly advancing in an endless path at one side of the channel, said path being so located that the member enters and leaves the channel in tilted position, the member being curved on its pushing face so as to leave the article with a sliding movement as the member tilts in its withdrawal from the channel and to bring the article gradually to rest against the stop and shaped to contact the partially wrapped article on one rear corner by pressing against said corner a portion of the wrapper throughout an area insufficient to form a permanent fold therein.

7. A wrapping machine comprising a wrapper folding channel, a pusher for forwarding an article along said channel having a sufficient extent in the direction of the channel to permit a wrapper folded around the article to extend rearwardly around the pusher, said pusher having an article engaging projection substantially flush with the forward end of the pusher and extending below the channel in a plane at right angles thereto a distance sufficient to permit full engagement between the pusher and the lower rear corner of the article but insufficient to prevent the wrapper from extending rearwardly beyond the article around the pusher, and means associated with the channel for folding a wrapper around the forward end and at least two adjacent sides of the article and around the article contacting portion of the pusher.
